UNITED STATES PATENT OFFICE.

JOSEPH A. PATTERSON, OF WAYNESBURG, PENNSYLVANIA.

GUN-RACK.

1,257,107.

Specification of Letters Patent. Patented Feb. 19, 1918.

Application filed April 15, 1916, Serial No. 91,346. Renewed January 19, 1918. Serial No. 212,827.

To all whom it may concern:

Be it known that I, JOSEPH A. PATTERSON, a citizen of the United States, residing at Waynesburg, in the county of Greene and State of Pennsylvania, have invented certain new and useful Improvements in Gun-Racks, of which the following is a specification.

The present invention relates to supports and more particularly to new and useful improvements in racks for firearms and the like.

The primary object of my invention is to provide a gun rack adapted to be supported by the post of a tent or the like, the gun rack being of a construction facilitating its application to various types of posts, regardless of whether the post is a tent pole or the like or not.

Another object of my invention is to provide a gun rack of the class described which is provided with a plurality of clamping members and sprockets whereby to receive and hold a plurality of rifles, the rifles being arranged preferably in a circle in order that in an emergency the rifles may be quickly grasped and removed from the rack with facility. In the following specification it will be noted that I have provided a gun rack having clamps and sprockets for eight rifles, but of course it will be understood that any number of the clamps and sprockets might be provided without materially departing from my invention. The shape of the gun rack might also be made to suit various contingencies.

Other objects and advantages to be derived from the use of my improved gun rack will appear from the following detailed description and the claims, taken with an inspection of the accompanying drawing, in which:

Figure 1 is a fragmental perspective view of a gun rack embodying improvements of my invention;

Fig. 2 is a fragmental top plan view of the gun barrel engaging member; and

Fig. 3 is a fragmental side elevational view of the gun stock receiving member.

Referring more particularly to the drawing, wherein similar characters of reference designate like and corresponding parts throughout the various views, 1 designates a post forming the usual tent pole which in the present type of tent extends vertically in the center of the tent. My improved gun rack embodies two elements, namely the gun

stock receiving member and the barrel receiving and clamping member. The gun stock receiver is designated 2 in its entirety and the barrel clamping member is designated 3.

Referring specifically to the member 2 the same preferably comprises two semi-circular plates 4 and 5 adapted to be connected by means of a pair of bolts, only one of which appears in the drawing, designated 6. The bolt 6 shown thus in Fig. 3 is provided with downturned ends 7 which engage in suitable openings in the plates 4 and 5, to retain them in position. The plates when connected provide a supporting disk like element, each of the plates 4 and 5 being provided with semi-cylindrical sections 9 and 10, respectively. The sections 9 and 10 embrace the pole 1 and are clamped thereabout by means of split collars 11 and 12, said collars being maintained in clamping engagement with said semi-cylindrical sections by means of wing nuts 13. A plurality of radially extending angular brace rods 14, 15, 16 and 17 secured on the sections 9 and 10 and the plates 4 and 5 serve to strengthen the supporting element 2.

The gun stock receiving means comprises a plurality of elliptical openings 18 and 19 formed in the plates 4 and 5, supporting stirrups 20 and 21 being arranged beneath said openings 18 and 19 to receive the gun stock and prevent the same from passing entirely through said openings. The stirrups 20 and 21 are riveted as at 22 to the plates 4 and 5 or are fastened in any other manner desired.

A plurality of hooks 23 depending from the plates 4 and 5 serve to carry cartridge belts, bayonets and the like. Of course, it is to be understood that the base member 2 is to be arranged on the pole 1 at a sufficient distance above the ground to permit of hanging of objects on said hooks.

Coöoperating with the member 2 I provide the member hereinbefore designated 3 and comprising two semi-circular plates 24 and 25 with complementary semi-cylindrical sections 26 and 27, respectively, carried thereby. Brackets 28 serve to connect said plates with their respective semi-cylindrical sections. A split collar 29 serves to retain the sections 26 and 27 in clamping engagement with the pole 1, a wing nut 30 serving to retain said collar in position.

Each of the plates 24 and 25 carries clamping means for engagement with the

barrel of a gun, said clamping means being thus shown in Fig. 2. To accommodate the gun barrel the plates 24 and 25 are provided with a plurality of recesses 31, the 5 brackets 32 being riveted at 33 to said plates. The U-shaped clamping spring element 34 carried by said bracket 32 serves to receive the gun barrels and retain the same against displacement. Of course, it will be understood that the distance between the members 2 and 3 on the pole is such as will accommodate the usual length of army rifle. However, the length of the gun or rifle does not materially affect the device in view of the 10 fact that the members 2 and 3 may be easily adjusted up or down on the pole.

In use it will be seen that the gun stocks are receivable on the stirrups 20 and 21 and the muzzles or barrels of the guns are received in the clamping elements 34. It will thus be seen that in the event of an emergency the guns may be quickly taken from the holder without the necessity of operating complicated catches or the like. It is also 25 to be understood that while I have described my invention as being particularly adapted for use as a gun rack I do not desire to be limited to its use in this capacity in view of the fact that by slight modifications the 30 same may be employed for supporting various articles.

From the above description taken in connection with the accompanying drawing, it is thought that a clear and comprehensive 35 understanding of the construction, operation and advantages of my invention may be had, and while I have shown and described my invention as embodying a specific structure, I desire that it be understood that I may 40 make such changes in said structure as do not depart from the spirit and scope of the invention as described.

Copies of this patent may be obtained for five cents each, by addressing the "Commissioner of Patents, Washington, D. C."

Having thus fully described my invention, what I claim as new and desire to secure by Letters Patent, is:—

45

1. In a device of the class described the combination with a vertical standard, of a supporting element formed of a pair of semi-circular plates adjustably connected with said standard, a clamping element formed 50 of a pair of semi-circular plates adjustably connected with said standard above the supporting elements, said clamping elements being of a smaller diameter than the supporting elements, and spring clips on said clamping element to receive and engage objects held by the supporting elements.

55

2. In a device of the character described, the combination with a vertical standard, of a supporting element formed of a pair of 60 semi-circular plates, a clamping element, said plates having semi-cylindrical collar portions projecting upward from the inner edges thereof and adapted to engage the standard, and means for releasably clamp- 65 ing said collars to the standard whereby the elements are vertically adjustable thereon.

70

3. In a device of the class described the combination with a standard having a supporting element carried thereby, of a pair 70 of semi-circular plates adjustably connected with the standard above the supporting element, said plates being disposed in a single plane, the plates being provided with a plurality of notches in the peripheral edge 75 thereof, brackets on said plates adjacent the inner ends of the notches, and spring clips carried by said brackets with the jaws thereof disposed substantially parallel with the sides of the notches to clamp objects therein.

80

In testimony whereof, I affix my signature hereto.

JOSEPH A. PATTERSON.
